UNITED STATES PATENT OFFICE.

EDWARD J. QUIGLEY, OF NEWARK, NEW JERSEY.

COLLAR.

1,091,017.

Specification of Letters Patent. Patented Mar. 24, 1914.

Application filed April 2, 1913. Serial No. 758,300.

To all whom it may concern:

Be it known that I, EDWARD J. QUIGLEY, a citizen of the United States, and a resident of Newark, in the county of Essex and State 5 of New Jersey, have invented certain new and useful Improvements in Collars, of which the following is a specification.

This invention relates to collars, more particularly to soft or negligée collars, and the 10 objects of the invention are to provide a soft or negligée collar which when in use will have many of the advantages of a stiff collar without the use of celluloid strips or similar separate stiffening means.

15 Further objects of the invention are to provide the collar with integral stiffening means that in no way interfere with the appearance, comfort or laundrying of the collar.

20 To the accomplishment of the above objects, and to such others as may hereinafter appear, the invention comprises a soft turned down collar, the inner portion, or neck band, of which is provided with additional plies of cloth, at the front ends of 25 the neck band and, adjacent the back button hole of the collar, said additional plies of cloth extending to the top of the neck band and adapted to be starched to hold the 30 soft portions of the collar in proper position.

Referring to the drawings: Figure 1 is a perspective view of a collar made in accordance with the invention. Fig. 2 is a plan view of the collar laid out flat, and Fig. 3 35 is a section of the collar taken through the back of the collar.

In the drawings: In the present instance A designates the neck band portion and B the top portion of the collar which is usually 40 made of two or more plies of linen, silk or cotton sewed together and cut to form a turned down collar such as shown in Fig. 1. The portions A and B of the collar are preferably made of continuous pieces of material, the top portion B and the neck band A being turned or folded along the line designated by the row of stitches C placed in position for this purpose.

In order to keep the collar upright when 45 in use the neck band is provided with additional plies of material adjacent the front and back button holes D and E. In the present instance the additional plies of cloth comprising the back supporting member F situated about the button hole E, are cut approximately in the shape of a semicircle

and sewed preferably to the back of the neck band of the collar, as shown in Fig. 2, the upper curved portion of the back supporting member F extending to the row of 60 stitches C marking the top edge of the collar, whereas the lower straight portion of the member F extends for a short distance on both sides of the button hole E. In the present instance the additional plies of cloth, 65 comprising the front supporting members G situated about the button holes D on the overlapping tabs of the neck band, are preferably cut and sewed to cover the tabs at one end, whereas the other ends are cut and 70 sewed on a diagonal line extending from the top of the tabs, or the row of stitches C, to the bottom of the neck band, as clearly shown in Fig. 2.

The front and back supporting members 75 F and G as above described, are preferably starched in laundrying, the remaining portions of the collar being left soft, the additional thickness of material comprising the front and back supporting members facilitating the starching and stiffening of the 80 collar at these places.

It will be seen from the above description that a collar so constructed will remain upright as shown in Fig. 1, the same being 85 held in this position by means of the front and back supporting members F and G, made integral with the collar and starched to accomplish this purpose. It is also to be noted that the button holes are in the supporting members and will retain the 90 collar buttons preventing them from turning and coming out, and that the diagonal extension of the front supporting members G and the broad lower portion of the back 95 supporting member F, insure the collar remaining in position on the neckband of the shirt to which the collar is attached, the upper part of the collar being left soft for the comfort of the wearer. The collar when 100 worn is very comfortable, stays in position, looks neat, is easily laundered and has no loops or extra parts to trouble the wearer, no buttons or similar uncomfortable means are required to hold the neck band together 105 in front as is required by other soft collars, the present collar overcoming all of these faults.

While the invention has been described with particular reference to the details of 110 construction, the same is not to be considered as limited thereto, as many changes

may be made and still fall within the scope of the following claims.

What I claim is:

1. A soft turned down collar comprising an inner neckband portion having button holes at its ends and middle and an outer turned down portion, and stiffening means secured to said neckband around said button holes and extending to the top of the neckband at the ends and middle, but spaced apart along the top of the neckband, whereby the top of the neckband is supported at the ends and middle but remains soft and unstiffened therebetween.
2. A soft turned down collar comprising an inner neckband portion having button holes at its ends and middle and an outer turned down portion, and stiffening means comprising extra plies of cloth secured to said neckband around said button holes and extending to the top of the neckband at the ends and middle, but spaced apart along the top of the neckband, whereby the top of the neckband is supported at the ends

and middle but remains soft and unstiffened therebetween.

3. A soft collar comprising a top portion and a neck band having end tabs, button holes in said end tabs and back portion of said neck band, front stiffening members comprising extra plies of cloth secured to said end tabs and extending from the top of said tabs rearwardly to the bottom of said neck band, and a back substantially semicircular stiffening member comprising extra plies of cloth secured to the neck band adjacent the back button hole and extending to the top of said neckband, whereby the upper portion of the neckband is supported at the ends and middle but remains unstiffened therebetween.

In testimony whereof I have signed this specification in the presence of two subscribing witnesses.

EDWARD J. QUIGLEY.
